POWER SUPPLY SYSTEM FOR SIGNAL RECEIVERS

Benjamin Singer, Bronx, N. Y., assignor to Hazeltine Corporation, a corporation of Delaware

Application June 1, 1936, Serial No. 82,776

9 Claims. (Cl. 250—27)

This invention relates to signal receivers, and more particularly to power supply systems for use in radio broadcast receivers.

In the manufacture of small receivers capable of operating from either an alternating current or direct current source, it is desirable to provide a power supply system of economical construction which is efficient in operation and is capable of supplying the necessary operating voltages and currents to the various tubes and the sound reproducing device of the receiver from either form of current source. A unidirectionally conducting device or rectifying tube is an essential element of such a system and, if this tube is to be of a cost commensurate with that of the other elements of the receiver, its current rating may be so low as to be exceeded if the conventional arrangement is utilized of paralleling the anode circuits of the tubes of the receiver and utilizing the field winding of the translating device or sound reproducer as a series-connected smoothing reactor. Also, in an alternating current—direct current receiver of this type, voltage step-up devices are not commercially feasible at the present time and, accordingly, the available voltage for the plate circuits of the receiver is limited to the voltage of the source which, in practically all instances, is that of a commercially current lighting circuit, or approximately 110 volts. Hence, if the field winding of the sound reproducer is connected in series with the parallel-connected plate circuits of the receiver to operate as a smoothing reactor and is designed to provide the necessary ampere turns to insure normal field intensity in the reproducer, the voltage drop thereacross may reduce the remaining voltage available for application to the vacuum tube anodes to a value considerably smaller than that necessary for satisfactory operation thereof unless the winding is made of such large wire as to be uneconomical and to occupy an excessive space.

It is an object of the present invention, therefore, to provide an improved power supply arrangement, for use in high-frequency signal receivers, which is of simple and economical construction and is highly efficient in operation.

It is a further object of this invention to provide an improved power supply arrangement of the above character which operates from either an alternating current or direct current commercial current lighting circuit, which includes elements of standard commercial construction, and which is effective in operation to supply substantially rated voltages to the anodes of the several

tubes included in the receiver and rated power to the translating device of the receiver.

Briefly, the above objects are attained in accordance with the present invention by providing, in a receiver of the general type noted above, a sound reproducing device having two field windings, one of which is connected in series with the rectifier or unidirectionally conductive device of the power supply system and the parallel related anode circuits of the receiver across the source of current supply, and the other of which is connected in the common path of the input and output circuits of one of the tubes of the receiver to operate as the cathode-biasing element for this tube. The latter winding is proportioned to provide the correct bias on the associated cathode and the two windings are proportioned in size so that together they comprise the necessary number of ampere turns to provide sufficient magnetic field strength in the sound reproducer for satisfactory operation thereof. By including one of the field windings in the cathode circuit of one of the tubes, the portion of the available voltage absorbed by the field winding is reduced without impairing the operation of the reproducer.

The novel features which are believed to be characteristic of this invention are set forth with particularity in the appended claims. The invention itself, however, both as to its organization and method of operation, together with further objects and advantages thereof, will best be understood by reference to the specification taken in connection with the accompanying drawing, in which Fig. 1 illustrates a radio receiver of the well-known superheterodyne type embodying the present invention, and Fig. 2 illustrates a modification of the invention.

Referring more particularly to Fig. 1 of the drawing, the invention is illustrated in its application to a radio receiver of the superheterodyne type. The receiver comprises a radio-frequency amplifier and modulator tube 10 having its input circuit 11 coupled to an antenna circuit 12 and its output circuit 13 coupled to the input circuit 14 of a detector 15. Volume control is obtained by the provision of an adjustable control grid biasing circuit for the tube 10 which comprises an adjustable resistor 16 having its active portion shunted by a condenser 17. A leak resistor 18 paralleled by a condenser 19 is provided in the input circuit of the detector 15 in the conventional manner. A local oscillator, indicated generally at 20, is provided which comprises the oscillator section of the pentagrid converter 10, a tunable oscillation circuit 22 and a feed-back cir-

cuit including an inductor 23. The tuning elements of the selector circuit 11 and the local oscillation circuit 22 are ganged for unicontrol adjustment, as indicated by the dotted line 25. The 5 output circuit of the detector 15 is coupled by means of a condenser 26, a resistance 27 and a condenser 28 to the input electrodes of an audio-frequency amplifier tube 29 having its output circuit, in turn, coupled through a transformer 30 10 to the signal coil of a sound reproducing or translating device, indicated generally at 31. The sound reproducing device 31 is provided with two field windings 32 and 33 which are connected in a power supply system indicated generally at 34, 15 constructed and arranged in accordance with the present invention, and are proportioned in size in a particular manner to be hereinafter described.

Screen grid and anode potentials are supplied to the tubes from the power supply system 34 20 through a common circuit lead 35, voltage dropping resistors 36, 37 and 38, and the inductor 23.

Considering the operation of the receiver as a whole, without regard to the details of the power supply system 34 per se, the desired received 25 signal wave is selected in the radio-frequency selector 11, and is converted to an intermediate frequency in the modulator tube 10. The modulated intermediate-frequency carrier wave thus produced is further selected in the circuits 13 30 and 14, is detected in the detector 15, and the signal-frequency components thereof are amplified in the audio-frequency amplifier 29 and reproduced by the sound reproducer or translating device 31.

Referring now more particularly to the power system 34, which is arranged in accordance with the present invention, the system comprises input terminals 40 and 41 which are adapted to be connected to a source of current (not shown). 35 Connected in series with the reproducer field winding 33 between the terminal 40 and the common screen and anode circuit lead 35 is a rectifier tube 39. The circuit between each of the anode circuits of the system and the current supply terminals 40 and 41 is completed by the connection of the terminal 41 to ground, whereby a current path is established between this terminal and the respective cathodes of the several tubes. For the purpose of interrupting the supply 40 of current to the receiver, a switch 42 is provided in the connection between the terminal 40 and the rectifier 39. The cathode heaters for the several tubes of the receiver and the tube 39 of the power supply system are connected in 45 series with each other, and with a voltage dropping resistor 43 between the terminal 41 and one terminal of the switch 42. In order to bias the cathode of the audio-frequency amplifier tube 29 to the proper potential relative to its associated 50 control grid, the second field winding 32 of the sound reproducing device 31 is connected between this cathode and ground, and, as thus connected, this winding is energized by the space current of the tube 29. Suitable filter condensers 44 and 45 are provided in addition to the winding 33 for smoothing the rectified output 55 from the tube 39 when the terminals 40 and 41 are connected to supply power to the receiver from an alternating current source. A high-frequency by-pass condenser 46 is also connected 60 between the terminal 40 and ground.

In describing the operation of the power supply system, it will first be assumed that the terminals 40 and 41 are connected to an alternating current source. As thus connected and with the

switch 42 closed, alternating current supply is rectified in the tube 39, is smoothed by the filter comprising the winding 33 and the condensers 44 and 45, and flows through the common lead 35 to the anode circuits of each of the tubes. 5 Alternatively, with the terminals 40 and 41 properly connected to a direct current source with such polarity that the rectifier 39 constitutes a low resistance to direct current, the direct current paths through the supply system and the 10 anode circuits of the tubes of the receiver are exactly the same.

The economy of construction resulting from the use of a rectifying device 39 having a low current rating has previously been mentioned, as 15 have also the requisites of minimizing the voltage drop between the current source and the anodes of the tubes and of providing an adequate number of ampere turns in the field windings of the reproducing device for insuring the production of a normal magnetic field strength therein, without the use of an inordinate amount of copper. These three desirable features are all attained, in accordance with this invention, by the arrangement described above, and by a proper 20 selection of the number of turns of the field windings 32 and 33. In this connection, it will be understood that the current rating of the rectifier tube 39 is determined by the sum of the space currents of the several tubes of the receiver, since 25 the anode circuits of these tubes in parallel determine the magnitude of current to be drawn from the source through this tube. The number of turns in the winding 32 and the size of the conductor used are chosen so that the voltage drop 30 across this winding caused by the space current of the tube 29 produces the correct positive bias on the cathode relative to the control electrode of this tube. The winding 33 is proportioned to provide the required amount of smoothing 35 reactance and the required number of field ampere turns without causing an unduly large voltage drop between the voltage supply source and the tube anodes, or using an excessively large size of conductor in the winding. The correct proportioning of this winding for a particular circuit design may best be worked out experimentally by 40 striking a compromise between the several factors noted.

While it will be understood that the circuit specifications may vary according to the design of a particular application, the following specifications of the circuit elements of Fig. 1 are included, by way of example, as having been found satisfactory when used in conjunction with a rectifier tube 39 45 commercially known as the 2525 tube.

Vacuum tube 10	Commercial type 6A7	
Vacuum tube 15	Commercial type 6C6	
Vacuum tube 29	Commercial type 43	
Resistance 43	Ohms	160 60
Condenser 28	Microfarads	25
Condenser 44	Microfarads	8
Condenser 45	Microfarads	8
Condenser 46	Microfarad	.05
Winding 32	{Turns, No. 34 gauge wire	5600
	Ohms	450
Winding 33	{Turns, No. 36 gauge wire	3850 65
	Ohms	650

Referring now to Fig. 2 of the drawing, there is illustrated a modification of the invention which differs from that of Fig. 1 only in the addition of a voltage dividing or bleeding resistor 46' 70 connected between the high potential terminal of the winding 32 and the low potential terminal of the winding 33, and having connected thereto a lead 47 for supplying a positive potential of the correct value to the screen electrodes of the tubes. 75

included in the first part of the modulated-carrier channel. In this figure the first portion of the receiver is omitted and the input to the tube 29 is indicated schematically at 48. The current drawn by the bleeding resistor 46 increases the magnitude of current through the winding 32 and this increase in current permits a decrease in the size of the field windings 32 and 33 without impairing the operation of the reproducer or the receiver circuit. This fact is emphasized by the following specifications for the sound reproducer field windings when used in conjunction with a resistor 46 of 2500 ohms, the other circuit specifications being the same as those given above:

15 Winding 32—3250 turns No. 34 wire—325 ohms
Winding 33—6150 turns No. 34 wire—450 ohms

It will be observed that, in either of the two modifications described above, the use of the 20 winding 32 in the cathode circuit of the tube 29 eliminates a separate cathode-biasing element from the receiver and, accordingly, eliminates one item of the cost of construction. It will also be observed that, with the windings 32 and 33 25 connected so that the magnetic fields produced thereby are additive, the windings are so poled with respect to each other as to prevent oscillation in the circuit of the amplifier 29 due to the coupling between these windings.

30 While there have been described what are at present considered preferred embodiments of this invention, it will be obvious to those skilled in the art that various changes and modifications may be made therein without departing from this invention, and, therefore, it is aimed in the appended claims to cover all such changes and modifications as fall within the true spirit and scope of this invention.

What is claimed is:

40 1. In a signal receiver, a translating device including magnetizing means, a vacuum tube including an anode, a control electrode and a cathode, an anode-cathode circuit for said tube including a source of space current and a portion 45 of said magnetizing means connected between said anode and said source, a control electrode-cathode circuit for said tube, another portion of said magnetizing means being common to said anode-cathode and control electrode-cathode 50 circuits to be energized by said space current and for providing a bias voltage for said control electrode.

2. In a signal receiver, a translating device including magnetizing means, a vacuum tube including an anode, a control electrode, and a cathode, a pair of input terminals adapted to be connected to either an alternating or direct current source of low voltage, an anode-cathode circuit for supplying space current to said tube from 60 said terminals comprising, in series between said anode and one of said terminals, a unidirectionally conductive device and a portion of said magnetizing means, a control electrode-cathode circuit for said tube, another portion of said magnetizing means being common to said anode-cathode and control electrode-cathode circuits to be energized by said space current and for providing a bias voltage for said control electrode.

3. In a signal receiver, a translating device including a pair of field windings, a vacuum tube including an anode, a control electrode and a cathode, an anode-cathode circuit for said tube including a source of current for supplying space current to said tube and for exciting said windings, a control electrode-cathode circuit for said

tube, one of said windings being included in said anode-cathode circuit between said anode and said source and the other of said windings being common to said anode-cathode and control electrode-cathode circuits and providing a bias voltage for said control electrode. 5

4. In a signal receiver, a translating device, a vacuum tube repeater including an anode, a control electrode, input and output circuits connected to said tube including a common current path, said translating device being coupled to said output circuit and including a pair of field windings, a pair of power input terminals adapted to be connected to either an alternating or direct current source of low voltage, a circuit 10 connected to said input terminals for supplying space current to said tube and serially including a unidirectionally conductive device and said field windings so arranged that said windings are excited by the space current of said tube, one 15 of said windings being included in said output circuit between said anode and said device and being effective as a smoothing reactance when said terminals are connected to an alternating current source and the other of said windings 20 being included in said common path for providing a bias voltage for said control electrode. 25

5. In a signal receiver, a translating device including magnetizing means, a plurality of coupled vacuum tubes each including an anode, a control 30 electrode and a cathode, input and output circuits for said tubes, a circuit for supplying power to said receiver from either an alternating or direct current source of low voltage including a unidirectionally conductive device and said 35 magnetizing means in series, a portion of said magnetizing means being included in said output circuits between said anodes and said source and another portion of said magnetizing means being common to the input and output circuits 40 of only one of said tubes, whereby said magnetizing means is energized by space current supplied to said tubes and said other portion of said magnetizing means provides a bias voltage for said 45 one of said tubes.

6. In a signal receiver, a translating device including magnetizing means, a plurality of vacuum tubes, each including an anode, a control electrode and a cathode, a circuit serially including a part of said magnetizing means for supplying space 50 current to said tubes and for exciting said magnetizing means, a portion of said magnetizing means being common to the anode-cathode and control electrode-cathode circuits of one of said tubes, voltage dividing means for supplying voltages to certain of the electrodes of said tubes connected in series with said portion of said magnetizing means to increase the excitation thereof, said portion of said magnetizing means having a resistance such that the total current therethrough provides a proper bias voltage for the control electrode of said one of said tubes. 55

7. In a signal receiver, a plurality of coupled vacuum tubes each including an anode, a cathode and a control electrode, a translating device including a pair of field windings, a pair of power input terminals adapted to be connected to either an alternating or direct current source of low voltage, and a circuit including the space current paths of said tubes in parallel, said circuit including a unidirectionally conductive device and one of said field windings connected in series between one of said terminals and a common connection to the anodes of said tubes, whereby said one of said field windings is energized and 70

is effective to smooth the space current of said tubes when said input terminals are connected to an alternating current source, and the other of said field windings being common to the anode-cathode and control electrode-cathode circuits of only one of said tubes, whereby it is energized by the space current flowing through said tube and the voltage developed thereacross provides a bias for said one of said tubes.

10. 8. In a signal receiver, a plurality of coupled vacuum tubes each including an anode, a control electrode and a cathode, a translating device including a pair of field windings, a pair of power input terminals adapted to be connected to either an alternating or direct current source of low voltage and a circuit including the space current paths of said tubes in parallel, said circuit including a unidirectionally conductive device and one of said windings connected in series between one of said terminals and a common connection to the anodes of said tubes, whereby said one of said windings is energized and is effective to smooth the space current of said tubes when said terminals are connected to an alternating current source, and the other of said field windings being common to the anode-cathode and control electrode-cathode circuits of only one of said tubes, whereby it is energized by the space current flowing through said tube and the voltage developed thereacross provides a bias for the control electrode of said one of said tubes, the resistance of said windings being proportioned substantially to provide normal rated voltage to said anodes, normal bias to said cathode, and

normal field excitation for said translating device with said terminals connected to either an alternating or direct current source.

9. In a high-frequency receiver, a plurality of coupled vacuum tubes each including an anode, a control electrode and a cathode, a translating device including a pair of field windings, a pair of power input terminals adapted to be connected to either an alternating or direct current source of low voltage, a circuit including the space current paths of said tubes in parallel, said circuit including a unidirectionally conductive device and one of said field windings connected in series between one of said terminals and a common connection to the anodes of said tubes, whereby said one of said windings is energized and is effective as a smoothing reactance when said input terminals are connected to an alternating current source, and the other of said field windings being common to the anode-cathode and control electrode-cathode circuits of only one of said tubes whereby it is energized by the space current flowing through said tube, and means comprising a voltage dividing resistor connected between the low potential terminal of said one of said windings and the high potential terminal of the other of said windings for passing additional current through said other of said windings to increase the excitation thereof, the resistance of said other winding being such that the total current therethrough provides a proper bias voltage for the control electrode of said one of said tubes.

BENJAMIN SINGER.
